UNITED STATES PATENT OFFICE

2,371,563

DIGGING IMPLEMENT

Leo N. Walter, Oak Glenn, Ill.

Application June 21, 1943, Serial No. 491,639

4 Claims.

(Cl. 255—67)

This invention relates to an improved digging implement of the kind employed for making holes for posts, poles and the like.

Various types of post hole diggers and augers have been marketed in the past. However for the most part they were crude and inefficient devices. Many of them were limited to definite depths or could be used only in sandy, loamy, or other light soil.

The present invention overcomes many of the disadvantages of former devices and provides an improved compact, and easily operated device. Moreover the improved device of this invention may be used in light or heavy soil for digging holes the depths of which are only limited by the length of the handle.

One of the principal objects of importance and advantage of the improved device of this invention resides in provision of means for producing a sturdy and rugged item from a relatively few associated and interdependant parts.

Another object of advantage and importance is the provision of means for utilizing a wedge acting mechanical advantage to operate the movable spade portion of the device.

Still another object of advantage resides in the provision of means for operating the device through a pair of manually operated telescoped tubes.

An additional object of importance and advantage resides in the provision of means for hingedly mounting movable spade members for limited movement toward and away from one another.

Additional objects of advantage and importance will become apparent as the following detailed description progresses, reference being had to the accompanying drawing wherein:

Fig. 1 is a front elevational view of a digger which embodies the invention. The dotted lines show the extent of movement in each direction of the movable spade portion of the device.

Fig. 2 is a side elevational view thereof.

Fig. 3 is a sectional view taken on line 3—3 of Fig. 2.

Fig. 4 illustrates a slightly modified form of the invention.

The reference numeral 10 indicates generally a substantially circular plate which forms the base portion of the improved device of this invention. The plate 10 is centrally apertured as is indicated by the reference numeral 12.

Secured to the base 10 and extending upwardly therefrom is a standard 14. The standard 14 may be formed from hollow, tubular or solid rod stock.

Telescoped onto the standard 14 and being adapted to move longitudinally thereof is a sleeve 16. Suitable handles 18 and 20 are secured to the upper ends of the standard 14 and the sleeve 16 as is best shown in Fig. 1.

Secured near the lower end of the sleeve 16 and movable therewith is an arm operating member 22. The arm operating member 22 is preferably positioned to extend at right angles to the sleeve 16 as is clearly shown in the drawing.

Pivotedly secured to the base 10 and being adapted to swing into and out of the path of travel of the arm operating member 22 is a stop 24. The stop 24 limits the downward travel of the sleeve 16 as will be hereinafter more fully disclosed.

Secured to the base 10 and projecting downwardly therefrom is a pair of spade members 26. Both spade members 26 may be hingedly associated with the base 10 as shown in Fig. 4 or one member 26 may be rigidly attached to the base 10 as is best shown in Fig. 1.

Projecting upwardly from the hingedly secured spade and being integral therewith is a spade operating arm 28. The spade operating arm 28 of each spade 26 is disposed angularly thereto as is best shown in Figs. 1 and 4. Each spade operating arm 28 inclines inwardly toward the sleeve 16 and the inner surfaces thereof are slidably engaged by the outwardly projecting end of an arm operating member 22. Movement of the sleeve 16 and the member 22 in an upward direction causes the lower end of the spade 26 to move radially inwardly and downward movement of the member 22 causes the lower end of the spade to move outwardly.

Formed in each spade operating arm 28 and extending longitudinally thereof is a bolt receiving slot 30. A bolt 32 passed through the slot 30 and screwthreadedly engaging the arm 22 provides means for holding the parts in operable association. Movement of the arm 28 outwardly or inwardly is positive.

In operation the improved device of this invention, while in normal position as shown in Figs. 1 and 4, is forced into the soil. When a sufficient bite has been obtained the handle 18 is drawn upwardly toward the handle 18 thus raising the sleeve 16 and the arm operating member 18. The upward movement of the member 18 forces the spade operating member 28 outwardly and the lower end of the hingedly mounted spade 26 inwardly. Soil trapped between the opposed spades 26, 26 is compressed and held as the implement is withdrawn from the hole being dug.

After the device is removed from the hole the handle 20 is forced downwardly restoring the spades to normal position as shown in Figs. 1 and 4. In the event the spades do not discharge the removed soil with dispatch the stop 24 may be swung radially outwardly to permit further downward travel of the arm operating member 22 and the further opening of the spades 26. In the wide open position dirt readily cleans from the spades 26.

It will be apparent from the foregoing that herein is provided a sturdy and rugged digging implement which may be universally employed for making holes in the ground, for removing obnoxious weeds by the roots and other like uses. Moreover the improved device may effectively be used by unskilled persons for making holes the depths of which are limited only by the length of the handle of the device. Additionally stoney or hard soil which prevents use of the auger type digger does not prevent use of the improved device of this invention.

It will also be apparent to those skilled in the art to which the improved device of this invention appertains that numerous changes and alterations in construction and design may be made without departing from the spirit or scope of the invention. Accordingly, the patent granted hereon is not to be limited to the previce embodiments here shown or in any other way except as is necessitated by the terminology of the appended claims when given the range of equivalents to which they may be entitled.

I claim:

1. In a digging implement, a substantially circular plate, a standard extending upwardly from the central portion of said plate, a tubular member telescoped over said standard, said tubular member being movable longitudinally of said standard, a stop member pivotally secured to said plate, said stop being movable into and out of the path of travel of said tubular member, a pair of spade members operably joined to said plate

on opposed sides of the peripheral edge thereof, an operating member secured to said tubular member and slidably engaging a portion of the upper part of said spade member providing means for operably moving the lower ends of said spades toward and from each other, and handles positioned on the upper ends of said standard and said tubular member for manually operating the device.

2. In a digging implement, a pair of spades disposed in opposed normally parallel relation to each other, a hinged mounting permitting the end of at least one spade to describe a limited arc, the upper end of said movable spade terminating in an angularly disposed channel shaped portion, an operating member slidably positioned in said channel shaped portion, manually operated means for moving said operating member in said channel shaped member, and a pivotally disposed stop member for limiting the radially outwardly movement of the lower end of said movable spade.

3. In a device of the kind described, a spade, an integral portion of the upper part of said spade being channel shaped in section, said channel shaped portion being disposed angularly in respect to the balance of the spade member, a stud receiving slot extending longitudinally of the channel shaped portion, an operating member slidably engageable with said channel shaped portion, and a securing stud extending through said slot and fixed in said operating member, said stud preventing separation of said operating member and said channel shaped portion.

4. In a device of the kind described, a base, a standard extending perpendicularly of said base, a tubular member telescoped over said standard, said tubular member being movable longitudinally of said standard, a stop member pivotally secured to said base, the free end of said stop member being movable into engagement with said standard to come into the line of travel and limit the movement of the tubular member.

LEO N. WALTER.
